SLITTER OR SCORER FOR TUBES OR SHEATHS

Edward Beyer, Oak Ridge, Tenn.

Application August 13, 1951, Serial No. 241,661

1 Claim. (Cl. 30—91)

1
This invention relates to tube and sheath slitters. The slitter herein disclosed may be employed, for example, in slitting the sheaths of electric cables.

An important object of the invention is to provide a slitter by which, after a sheath is inserted therein, the slitter may be moved longitudinally of the sheath and a pair of spaced-apart slits or scores will be made in the sheath but there will be no material binding of the sheath and slitter while the latter is being operated, whereby operations may be quickly accomplished.

Another important object is to provide a slitter which comprises easily machined parts and with all parts being simple and inexpensive to manufacture, yet the slitter is sturdy and adapted, for that reason, to accommodate sheaths or tubes of tough material, or, by the substitution of parts, will readily slit or score sheaths or tubes of relatively small diameters or of relatively thin, readily-slitted material.

A further important object is to provide a tube and sheath slitter adapted to employ a pair of spaced-apart cutters, moved into and out of slitting relationship with a member to be slit, solely by the use of a single screw means, and so that both cutters will enter the member to substantially the same depth. Where two or more screws are employed in order to cause two cutters to slit to an equal depth, unless both screws are manipulated carefully, one cutter may not cut through the member sufficiently for a portion to be removed while the other cutter may cut deeper than desired.

Additionally, an important object is to provide for sliding movement of the sliding parts of the slitter in substantially straight paths without deviation and without canting of any part.

Other objects and advantages of the invention will be apparent during the course of the following detailed description of the invention, taken in connection with the accompanying drawing, forming a part of this disclosure, and in which drawing:

Fig. 1 is a side elevation of the new slitter with a sheath being slit.

Fig. 2 is a vertical section of the slitter, substantially on the line 2—2 of Fig. 1.

Fig. 3 is a vertical section, substantially on the line 3—3 of Fig. 2.

Figs. 4, 5 and 6 are horizontal sections, substantially on their respective lines of Fig. 1.

In the drawing, wherein for the purpose of illustration is shown a preferred embodiment of the invention and wherein similar reference characters designate corresponding parts throughout

the several views, the letter A designates the new slitter and B a member being slit thereby.

The new slitter A includes an open-sided housing 10 formed of a pair of end portions comprising spaced-apart, paralleling channel bars 11 with their channels 12 and longitudinal edges 13 in facing relationship. These end portions are joined together at adjacent like ends by a bearing portion 14 accommodating a screw-threaded shank to be subsequently described. This bearing portion 14 is well shown in top plan in Fig. 4 and includes oppositely-disposed arms or end parts 15 snugly accommodated in portions of the channels 12 and with parts in contact with adjacent parts of the edges 13. The portion 14 has a central screw-threaded bore 16 and, extending into each arm 15, is a screw-threaded socket 17 with its axis substantially normal to the longitudinal axis of the bore 16. The bearing portion 14 is detachably secured to the end portions 11 as by screws 18 with their shanks extending through suitable openings in the end portions 11 and into the sockets 17.

Opposite the bearing portion 14 and forming another wall of the housing 10 as well as a support for a part of the slitter structure, is an end piece or portion 19, shown in Fig. 3 for example, which may be a block of suitable metal with its end parts snugly accommodated in parts of the channels 12 and this portion 19 has a pair of faces 20 facing the bearing portion 14 and each sloping from a bearing arm 21 (extending toward the portion 14) to a central bearing arm 22 which also extends toward the portion 14. The portion 19 is provided with screw-threaded sockets 23 (as four) to receive the shanks of screws 24 extending through suitable openings in the end portions 11 for the purpose of firmly securing the end portions 11 and end portion 19 together. The arms 21 and 22 are provided with axially-aligned bores 25 for the pivots of rollers 30 to be next described.

Carried by the support portion 19 is end means for the sheath and this means comprises a pair of rollers 30 having pivots 31 extending through the bores 25 as in Fig. 3. It will be apparent that the rollers 30 may be inserted into the spaces between the arm 21 and arm 22 and the pivots 31 slid into the bores 25 and the openings 32 extending through the rollers 30. The free end of the arm 22 does not extend to the outer peripheries of the rollers, as is clear in Fig. 3.

Slidable longitudinally of and within the housing 10 is a cutter support means including a cutter holder 35 which is somewhat T-shaped, and 55 may comprise a relatively wide block or arms 36

having end parts slideable within the channels 12 and parts slideable along the edges 13 and a narrower block or body 37 extending from the block 36, as in Fig. 3. The blocks may be detachably secured together as by the screws 38 the shanks of which may extend through openings in the block 36 and into screw-threaded sockets in the block 37.

The block 36 has a central, inverted T-shaped recess 39 for the free end portion of a screw to be subsequently described. This recess extends to one side face of the block 36 and the narrower part of the recess opens toward the bearing portion 14.

At the free end portion of the block 37 there are a pair of parallel slots 40 to accommodate portions of roller cutters 45 and there is provided a suitable bore 41 through the block 37 from its opposite ends to the slots 40. This bore 41 may contain the shank of a screw 42 since one part of the bore 41 may be screw-threaded to cooperate with the screw threads of the screw 42.

The cutters 45 are mounted for rotation upon smooth portions of the peripheries of the screw 42 with the cutting edges of the cutters 45 projecting outwardly of the ends of the slots 40.

Means to move the cutter support means 35 to 42 inclusive, toward and away from the rollers 30 and retain it in a selected moved position, is an elongated screw 50 having a head 51 to afford a hand grip, a screw-threaded shank 52 extending through the central screw-threaded bore 16 and an inverted T-shaped free end portion 53 accommodated in the inverted T-shaped recess 39 for rotation therein.

The new slitter may be constructed of iron or steel or of part iron or part steel, and the width of the same is such that it may be readily grasped by the hands. One hand may grasp the slitter in such a way that the protruding end of the shank 52 will rest upon that part of the hand between the bases of the thumb and index finger and the other fingers in contact with one end portion 11, while the other hand is cupped about the opposite portion of the slitter preferably with the ball of the thumb contacting one face of the end portion 18 and with one of the longitudinal edges 13 forming shoulders to prevent slipping of the thumb, while the balls of several of the fingers contact the other face of the end portion in order to effect a steady grip.

Initially, the screw 50 is rotated until the space between the rollers 30 and edges of the cutters 45 is sufficient for insertion of the member B of which the sheath 60 is to be slit and, after the proper length of sheath is inserted, the screw 50 is rotated to cause the cutters 45 to sink into the

sheath whereupon the slitter A is grasped and drawn longitudinally of the sheath, slitting it in two parallel lines so that the portion of sheath between the two lines may be peeled off, enabling the operator to remove, too, the rest of that portion of the sheath 60 to be removed.

Since there is a loose connection between the screw 50 and the block 36 of the cutter holder 35, a holder having cutters more widely or more closely spaced apart may be substituted, or even another block substituted for the block 37 by unscrewing the screws 38 and removing the block 37 with its cutters attached.

Moreover, the need for manipulating only one part (the screw 50), in order to operate the slitter is of advantage. This is accomplished although two cutters are employed, because of the sliding fit of the cutter holder 35 in the channels 12 of the channel irons, for the cutter holder cannot tend to cant, despite but one screw 50.

Various changes may be made to the form of the invention herein shown and described without departing from the spirit of the invention or scope of the claim.

What is claimed is:

A slitter for sheathed and tubular members, including a housing having spaced-apart channel bars including side walls having edge faces and providing longitudinal edges with the longitudinal edges of one side wall facing the longitudinal edges of the other side wall, a bearing portion bridging said channel bars, extending into the channels of the channel bars and secured to said bars, an end portion spaced from the bearing portion and bridging said channel bars and secured thereto, having side faces with end parts thereof extending into said channels with said side walls overlapping said end parts and said edge faces exposed, whereby said end portion may receive portions of the cupped hand of an operator; cutter means carried by said bearing portion and extending toward said end portion; and support means for said members carried by said end portion, and facing said cutter means.

EDWARD BEYER.
